UNITED STATES PATENT OFFICE.

EWALD LANGENOHL, OF WERMELSKIRCHEN, GERMANY.

PROCESS FOR MANUFACTURING WELTED BOOTS AND SHOES WITHOUT LASTING.

1,138,961.

Specification of Letters Patent.

Patented May 11, 1915.

Application filed May 22, 1909. Serial No. 497,680.

To all whom it may concern:

Be it known that I, EWALD LANGENOHL, manufacturer, subject of Prussia, residing at Wermelskirchen, in Rheinland, Germany, 5 Wustbachstrasse 2, have invented new and useful Improvements in Processes for Manufacturing Welted Boots and Shoes Without Lasting, of which the following is a specification.

10 The present process is for the purpose of dispensing with the use of lasts when manufacturing welted foot-gear, or at least considerably to restrict the use of the same, and thus avoid the considerable outlay of 15 capital and working expenses incurred in shoe factories by the purchase and maintaining of lasts, and at the same time of avoiding the hand labor incurred in placing the uppers on the last.

20 The process according to this invention is carried out in the following manner:—First the upper is sewed together from the usual parts, which, however, are not cut with a broad projecting portion on the lower edge 25 but are cut exactly to the outline of the form to be produced. Then the welt, in the form of a strip of strong fairly stiff leather, is sewed around the edge of the lower opening of the upper. Then by means of suitable 30 pressing devices, utilizing the welt for holding together the upper connected with it, the toe portion, and then the heel portion of the upper, are pressed into the shape of the finished boot and at the same time the welt 35 is adjusted parallel to the plane of the sole. Then when the actual shaping of the boot or shoe is essentially finished, the sole is fitted to the welt and provisionally fastened so that subsequently, the shoe can be closed by 40 sewing together the welt and the sole.

Figure 1 shows in side elevation an upper sewed to the welt. Fig. 2 is a side elevation of a pressing device serving for carrying out the present process. Fig. 3 shows a plan 45 view of both the parts serving on the one hand for holding and on the other hand for pressing the boot or shoe. Figs. 4 and 5 show the working of the pressing device when forming the toe portion. Fig. 6 shows 50 the working of the pressing device when forming the heel portion. Fig. 7 is a longitudinal section through a finished boot. Fig. 8 is a plan view of Fig. 7 as seen from 55 below. Fig. 9 is a cross-section through the finished boot showing the method of attaching the sole. Fig. 10 shows the use of an

auxiliary device which may be conveniently utilized when provisionally attaching the sole.

In carrying out the present process the 60 various portions of the uppers are cut in the usual manner but considerably closer on the sides corresponding to the lower edges, than is necessary when carrying out the ordinary tacking process. Then the 65 portions of the uppers are joined together in the usual manner so that they form the upper 1. Then by means of a strong machine stitch the leather strip 2, forming the welt, is sewed on parallel to the lower edge 70 of the upper, and not only around the front portion of the shoe but also around the heel. In order to obtain a very strong watertight connection between the upper and the welt, as well as to avoid the formation of 75 any folds when shaping the boot, more particularly in the toe portion at the edge of the upper and in the welt, both parts are furthermore sewed with a second machine stitch 4 running parallel to the first seam 3. 80 For the shaping of the foot gear subsequently to this preliminary preparation it is of the utmost importance that the shape of the foot gear is essentially determined on the one hand by the shape of the toe 85 part and on the other hand by the shape of the heel part. The curving of these parts, even when the shoe has not yet been closed at the bottom by the sole, imparts to the foot gear a shape-retaining rigidness, especially when these parts, as is usual, are stiffened by means of stiffening caps. The shape of the side pieces of the shoe, however, is determined in the lower part essentially by the course of the line along which 90 they are connected with the sole. Taking this into consideration according to the present process, the curved shape which the toe part and the heel part should have in the finished shoe is imparted successively, 95 on the one hand to the toe part and on the other hand to the heel part, by pressing, whereas the shape of the side parts is first determined on connecting up the welt with the sole. For shaping these curved parts 100 a device such as shown in Fig. 2 or like device is employed with advantage. This device consists of a frame 5 in the one vertical arm of which a pressure spindle 6 is 105 so arranged that it can be moved forward or backward by means of a screw and a nut, the latter being provided with a hand wheel

The press head 7 is fitted to the end of this spindle 6, which head 7 as may be seen from Fig. 2 and from the plan view of Fig. 3, is for example of the same shape as the interior of the toe part of the boot. A supporting plate 8 is fastened to a second arm of the frame 5 at the height of the sole surface of this press head 7 directly opposite the latter. This supporting plate or block 8, on its edge turned toward the pressure head 7, is provided with a recess corresponding to the toe part of the shoe or more exactly to the shape of the seam connecting the upper and the welt together, that is to say of the seam 4, of the finished shoe. The shaping of the toe part by means of this device is so effected that by bending in the heel part beneath the spindle 6, as may be seen from Fig. 4, the upper is placed over the press head 7 and after bending the welt 2 down into the plane of the sole the toe, part of the upper is pushed into the recess of the supporting block 8. Then the head 7 is moved step by step forwardly until it reaches the end position shown in Fig. 5. By this means, the upper is supported against the edge of the recess of the supporting block 8 and the welt, resting on the top of this plate 8, the upper is prevented from slipping off from the same and consequently the desired shape of the toe can be imparted to the upper by means of the press head 7, the seams 3 and 4 preventing the formation of any folds in the upper. The edge strips of the upper, as well as of the welt, are held together by the seams and are only subjected to the slight change of form resulting from the permanent turning over of the welt into a position parallel to the upper surface of the supporting block 8, that is to say, in the plane of the sole, the outer edge of the welt undergoing a certain extension. The shaping of the heel part is effected in an exactly similar manner by means of the same or of a similar press device in which the head 7 is substituted by a corresponding head 9 and the supporting plate 8 by a similar plate with a recess corresponding to the heel part. When pressing the heel part, as may be seen from Fig. 6, the already shaped toe part is bent down until the movement of the pressure spindle 6 is not prevented, this being easily possible owing to the flexibility of the sides of the upper.

The pressing process brings the upper into the shape as shown in Figs. 7 and 8. The welt bent down in the front and the back into the plane of the sole also adjusts itself between both the shaped ends in the plane of the sole. Thus without any difficulty, as may be seen from Fig. 9, a suitably cut sole 10 may be placed on the bottom opening of the shoe, which sole is previously prepared for the final fastening by being provision-

ally stuck to the welt by means of cement or in some other suitable manner. By suitably cutting the sole and fitting the welt along the edge of the same, the shape of the side parts can also be finally determined, without necessitating the use of a last for this purpose. In many cases, however, it is preferable to use a last when cementing on the sole and when finally attaching the same. Inasmuch as, however, both these operations only occupy but a very short time and as furthermore the last is not exposed to moisture nor to be damaged by nails and the like, even in such cases the number of lasts necessary for a certain production is considerably reduced and the lasts can be used for a much longer period before being worn out.

In order to facilitate the attaching of the sole and the correct shaping of the side parts, a templet 11 consisting of several parts is advantageously made use of. This templet has a recess formed in it corresponding to the bottom shape of the shoe and at the edge is so sharpened that its parts can be inserted into the groove between the upper and the welt. When fastening on the sole 10 this templet maintains the correct shape and furthermore serves as counter-support for pressing the edge of the sole on to the welt when cementing on the former.

As may be seen from Fig. 9 in dotted lines at 12 the necessary inlay for equalizing the thickness of the welt and the upper can be fastened subsequent to or previously to the fastening of the sole 10, on to the inside of the latter by means of any suitable paste or in some other suitable manner; an inner sock 13 may also be placed on this intermediate layer.

The final fastening of the sole 10 is suitably effected by the usual strong machine sewing, which passes through the outer edge of the welt and of the sole. The heel pieces are fastened to the sole by means of nails, screws or the like. Any necessary joint stiffening parts are arranged as usual in the shoe within the hollow space which exists between the inwardly bent edges of the upper and of the welt and which, as mentioned, is filled up in the front part of the shoe by packing. To the sole 10 serving for closing the shoe other sole pieces or treads may be fastened in the usual manner.

What I claim and desire to secure by Letters Patent is:—

The herein-described method of constructing a boot or shoe, which consists in securing a welt around the entire margin of an unsoled upper blank prior to the shaping of said upper, and in bending said welt downwardly and away from said upper blank into a plane approximately parallel with the plane of the tread face of the boot or shoe, and in successively applying pressure

to the interior and exterior of the toe and heel portions of the upper to shape said parts, and in applying pressure to the exterior of the sides of the upper between the 5 welt and the lower margin of the upper, and applying a sole, substantially as described.

In testimony whereof I have signed my name to this specification in the presence of two subscribing witnesses.

EWALD LANGENOHL.
